SIFTER PACKAGE FOR PHARMACEUTICALS

Mack R. Fields, Chicago, Ill., assignor to Abbott Laboratories, a corporation of Illinois

Application January 6, 1944, Serial No. 517,212

6 Claims. (Cl. 206—63.2)

1

This invention relates to the packaging of powdered or similar pharmaceutical preparations in a manner in which the preparation may be maintained in a sterile condition and conveniently dispensed by sifting directly from the package. The package herein described is designed particularly for the packaging of certain sulfa drugs in granular form which are employed in surgery by being sprinkled or sifted into the incision or into open wounds for control of infection.

The main objects of the invention are to provide a package of the character indicated, the component parts of which may be manufactured by more or less conventional envelope-making machinery and thereby produced in large numbers at a high rate of speed; to provide such a package which may be easily opened by the person about to use it immediately before sifting material from the package into the incision or wound; to provide such a package which will be effective to maintain its contents sterile notwithstanding the ease with which the package may be opened; to provide a sifter type of package which may be easily and quickly filled and assembled; and, in general, it is the object of the invention to provide an improved package of the character indicated.

Other objects and advantages of the improved package will be understood by reference to the following specification and accompanying drawings, wherein there is disclosed a package embodying a selected form of the invention, together with the method of opening the package preparatory to dispensing the contents thereof.

In the drawings,

Fig. 1 is a plan of a blank from which an outer envelope is formed;

Figs. 2 and 3 illustrate successive steps in folding the blank of Fig. 1 to form the outer envelope;

Fig. 4 is a plan showing the outer envelope completely formed, an inner envelope being also represented in place in the outer envelope;

Fig. 5 is a plan of a blank from which there is formed an inner envelope;

Fig. 6 is a perspective illustrating the blank of Fig. 5 partially folded to form the inner envelope;

Fig. 7 is a perspective illustrating the finished inner envelope in its closed condition;

Fig. 8 is a plan of the upper or sifter end of the inner envelope in the partially folded condition illustrated in Fig. 6;

Figs. 9, 10 and 11 are side elevations, Fig. 10 being partially in section, illustrating successive steps in the closing of the sifter end of the inner envelope;

Figs. 12, 13 and 14 are perspectives illustrating successive steps in the opening of the package preparatory to dispensing the contents of the inner envelope, and

2

Fig. 15 is a perspective illustrating the method of opening the sifter end of the inner package for dispensing purposes.

Referring now to the drawings, the outer envelope consists of a suitable paper blank having a main wall-forming panel 15. From the opposite sides of the panel 15, there extend flaps 16 and 17 which are adapted to be folded inwardly over the panel 15 to form the second or other side wall of the outer envelope. The flap 16 has its margin coated with adhesive, as indicated at 18, and such adhesive engages the outside surface of the flap 17, as will be apparent from an inspection of Fig. 2, to permanently unite said flaps and to hold them in their co-operating wall-forming position. The upper end portions of the flaps 16 and 17 have corner portions cut away, or recessed, and the remaining narrow upper portions are slotted transversely at an angle, as shown at 19 and 20, and also scored, perforated or otherwise weakened longitudinally, as indicated at 21 and 22. As shown, the slits 19 and 20 terminate short of the lines 23 and 24 on which the flaps 16 and 17 are folded relative to the panel 15 and, in the folded condition of the flaps, the tear lines 21 and 22 extend upwardly and slightly inwardly from the inner ends of said slits.

From the upper end of the panel 15, there projects a flap 25 to which there is applied spaced rectangular areas 26 and 27 of adhesive and also a thin stripe 28 of adhesive. The thin stripe of adhesive 28 has side portions located closely adjacent but spaced inwardly from the side edges 29 and 30 of the top flap 25 and transversely extending portions 31 and 32 disposed at such an angle that they meet in an obtuse angle, as shown at 33. When the flap 25 is folded to closed position over the previously folded side flaps 16 and 17, the adhesive areas 26 and 27 will engage the upper portions 34 and 35 of the side wall flaps, said portions being partially defined by the respective slits 19 and 20 and tear lines 21 and 22. The narrow stripe 28 of adhesive will engage the marginal portions of the wall-forming flaps 16 and 17 outwardly of the tear lines 21 and 22 and below and substantially parallel to the inclined slits 19 and 20 and the upper edges of said flaps intermediate the adjacent ends of said slits.

The blank of Fig. 1 may, of course, be formed by conventional envelope blanking machinery, and it may be folded by conventional envelope machinery to the open-ended envelope condition illustrated in Fig. 3. In that condition, the outer envelope is ready to have inserted thereinto an inner envelope containing the pharmaceutical preparation (or other material).

The inner envelope is preferably of the construction shown in Figs. 5 to 11 inclusive. It is formed from a blank having the form illus-

trated in Fig. 5 and which comprises a main panel 36, side flaps 37 and 38 extending from the side edges of said main panel, and top and bottom flaps 39 and 40 respectively extending from the top and bottom ends of the said main panel 36. The flap 37 is provided with a stripe 41 of adhesive extending longitudinally thereof adjacent but spaced inwardly from the free side edge thereof, and it is folded inwardly over the main panel 36 and over the side flap 38 which is initially folded inwardly over the panel 36. The flaps 37 and 38 are thus adhesively united to form the second side wall of the inner envelope, the main panel 36 forming the first wall.

The upper end flap 39 embodies an outer end portion 42 and inner portions 43 and 44. The portion 42 is connected to the portion 43 by a suitable fold line 45, and the portions 43 and 44 are similarly connected to each other by a fold line 46, the portion 44 being connected to the end of the panel 36 by a fold line 47. The sections 43 and 44 have their ends notched, as indicated at 48 and 49 respectively and they are provided with a plurality of suitably spaced diamond-shaped openings 50, which have their major dimension extending transversely of the intermediate fold line 46, and their minor dimension parallel to and in alignment with said fold line 46.

After the side flaps 37 and 38 are folded into the wall-forming position illustrated in Fig. 6, the top end flap 39 is folded through the steps illustrated in Figs. 6 to 11 inclusive to form a sifter end closure and to close the upper end of the envelope. The upper end flap sections 43 and 44 are folded into face-to-face engagement or to a position approaching such face-to-face engagement, as clearly shown in Figs. 6 and 9; then the side edges of the partially formed envelope are pressed toward each other so as to cause the side walls thereof to bulge and separate as shown in Figs. 6 and 8. When the envelope is thus caused to open, it will be observed that the inwardly notched ends 48 and 49 of the flap sections 43 and 44 cause the ends of the folded sections to lie within the open end of the envelope, and the V-shaped notches in each section 43 and 44 serve to facilitate curving of the folded flap portions 43 and 44 into conformity with the curvature of the wall 36.

The next step in the folding of the sifter end of the envelope is to fold the flap portion 42 downwardly over the upper end of the wall formed by the flaps 37 and 38, thereby incidentally turning the folded sections 43 and 44 downwardly into the open end of the envelope, as shown in Fig. 10. Upon completion of the downward folding of the flap section 42, the upper end of the envelope may again be flattened or closed, the sections 43 and 44 being then brought into face to face engagement with each other and with the respective walls of the envelope so that the said sifter end is effectively closed. The flap section 42 may be adhesively secured in closed position by the provision of a suitable stripe 51 of adhesive on the inside surface of the flap section 42.

The adhesive employed in the construction of the inner envelope is applied in spaced relation to the edges of the various flaps so that when the flaps are folded to their closed positions, adhesive will not be squeezed out beyond the edges of the flaps, the outside of the envelope being thereby maintained clean and free from

any cause of adhesion to the walls of the outer envelope.

The inner envelope may be filled with the desired quantity of sulfanilamide, or other pharmaceutical preparation or material, through the remaining open bottom end of the envelope whereupon the open bottom end may be closed by folding the lower end flap 40 over the open end to the position illustrated in Fig. 7. The flap 40 may be adhesively secured in its closed position as indicated.

The inner envelope with its content of material may then be inserted through the open bottom of the outer envelope illustrated in Fig. 3. During the handling of the inner envelope, suitable precaution is, of course, exercised to maintain the sifter end in its flattened closed position, as illustrated in Figs. 7 and 11, so that the content of the envelope will not be discharged through the sifter end. After the inner envelope is inserted into the outer envelope, a flap 52 which projects from the lower end of the main panel 16 of the outer envelope, is folded into closed position overlying the outer envelope wall formed by the flaps 16 and 17. The said bottom flap 52 may be provided with a suitable coating of adhesive, as indicated at 53, which will adhesively secure the flap 52 to the wall-forming flaps 16 and 17 so as to maintain the outer envelope closed.

The package formed as above described may be made of a suitable grade of paper, preferably a strong, fine-grain paper which is not excessively porous. The entire package is then preferably subjected to a sterilizing treatment which may consist of a dry heat treatment for a period of about two hours at a temperature of around 285° F.

Tests have indicated that when the package is formed as above described, and sterilized in the manner indicated, it will remain sterile indefinitely at least so far as the interior of the outer envelope and the inner envelope are concerned. Some care should, of course, be exercised to make sure that the adhesive stripe 28 which seals the upper end flap of the outer envelope to the body thereof forms an imperforate line of junction between the flap 25 and the wall formed by the flaps 16 and 17, and also that sufficient adhesive is applied to the lower flap 52 to hold the said flap in tight face-to-face engagement with the underlying wall of the envelope. It is perhaps not essential that adhesive be employed between all of the area of the flap 52 and the underlying surfaces of the envelope, but it is desirable that care be exercised to insure tight folding of the flap over the end of the envelope so that there remains no distended opening between the flap and the underlying wall of the envelope. The same consideration is applicable in respect of the sealing of the upper flap 25 to the underlying wall of the envelope.

The preferred method of opening the envelope so as to maintain sterility of the inner envelope, or at least, so as to avoid contamination of the dispensing end portion of the inner envelope, is illustrated in Figs. 12, 13 and 14. As there shown, the body of the package may be grasped in one hand while an unsecured marginal end portion of the top flap 28 is gripped between the fingers of the other hand preparatory to pulling said flap upwardly and away from the envelope wall to which it is adhesively attached. Separation of the adhesive joint formed by the adhesive stripe 28 is facilitated by reason of the angular disposition of the portions 31 and 32 of the

said adhesive stripe which results in a point 33 in which the tearing force is initially localized and from which the separation proceeds gradually toward each side. Such progressive separation is much easier to accomplish than would be the simultaneous separation of the entire length of an equivalent transverse line of adhesive. In the course of unfolding the flap 25, the adhesive connections between the flap and the portions 34 and 35 of the side walls are not separated but, instead, said portions 34 and 35 are separated from the wall of the envelope. This result is assured by proper regulation of the amount and character of the adhesive employed in the areas 26 and 27, and by the provision of the slits 19 and 20 and weakened tear lines 21 and 22. For manufacturing convenience, slight bonds may be retained in the slit lines 19 and 20 near the inner edges of the flap portions 34 and 35, although such bonds are not essential. Such bonds may be provided as indicated at 53-53 in Fig. 1. The bonds should be sufficiently narrow that they will not interfere with the separation of the portions 34 and 35 from the envelope wall along the full length of the slit lines 19 and 20.

The unfolding movement of the flap 25 is continued rearwardly until the flap may be tucked between the fingers of the hand holding the body of the envelope, as shown in Fig. 14, such folding of the flap being also accompanied by supplementary folding of the body of the outer envelope transversely along a line extending approximately at the level of the outer ends 54-54 of the upper edges of the envelope wall formed by the removal of the portions 34 and 35. The angular disposition of the tear lines 21 and 22 facilitate such folding by maintaining to a minimum the width of the side wall areas 55-55 (Fig. 13) at the line of fold. Said angular disposition of the tear lines 21 and 22 serves also to provide adequate width of wall with which the side portions of the adhesive stripe 28 may be engaged, while also holding down said width sufficiently to avoid substantial (if any) overlap of these portions on the inner envelope.

By the opening procedure described, the inner envelope is caused to project substantially from the outer envelope, the sifter end of the inner envelope being thus exposed. A surgeon about to employ the contents of the inner envelope, in the exercise of due caution, may then withdraw the inner envelope by means of a pair of forceps, or the like, and proceed to sift the contents of the envelope into an incision or wound. However, the use of forceps is not a necessity, inasmuch as a surgeon may grasp the inner envelope at a point spaced substantially from the sifter end and withdraw it from the outer envelope. Then, by pressing together the edges of the inner envelope near its sifter end, the walls thereof may be caused to bulge and the sifter end distended, as shown in Fig. 15, to thereby open the diamond-shaped dispensing openings, whereupon the contents of the envelope may be dispensed as required.

It will be apparent that the described envelope structure may conveniently be employed by members of the armed forces under battle conditions. In the case of wounds received under such conditions, the wounded person, if not wholly incapacitated, may easily open the described package 70 structure and sift the contents of the inner envelope into his wounds before sufficient time for serious infection has elapsed. Accordingly, many otherwise serious infections may be prevented in their inception.

When the inner envelope is inserted into the outer envelope, it is desirable that some care be exercised to center it therein so that when the package is opened, the inner envelope will be substantially midway between the tear lines 21 and 22, thereby to avoid overlapping of the inner envelope by the side wall areas 53 and 55 of the outer envelope. The length of the inner envelope is preferably such as to fit snugly within the length of the outer envelope; this close-fitting relation, together with the pinching or gripping effect of the walls of the outer envelope on the inner envelope serves to effectively hold the inner envelope against sidewise shifting in the outer container.

10 The described structure is capable of some modification without departing from the principles of the structure and such modifications are accordingly intended to be covered by some of the appended claims.

I claim:

1. A package of the class described comprising an inner container, an outer envelope enclosing said inner container, said envelope having a pair 25 of walls and a closure flap extending from the upper end of one of said walls, said flap being folded over the outside of the other wall to close the envelope, said other wall being provided with a centrally disposed opening in its upper end and with weakened lines of severance extending outwardly from the side edges defining said central opening, into proximity to the outer edges of the envelope, and thence upwardly toward the upper end of the wall, said lines of severance defining 30 readily removable inner corner portions, said flap being adhesively secured to said removable corner portions and also to the wall of the envelope below said corner portions, said envelope being adapted to be opened by pulling said flap from said other wall so as to break the adhesive bond 35 between the flap and said wall below said removable corner portions, the adhesive bond between said flap and said removable portions being of such strength that said removable portions will remain united to the flap and be removed from the envelope wall to thereby form in said envelope an opening affording free access to said inner container.

2. A package of the class described comprising 50 an inner container, an outer envelope enclosing said inner container, said envelope having a pair of walls and a closure flap extending from the upper end of one of said walls, said flap being folded over the outside of the other wall to close the envelope, said other wall being provided with a centrally disposed opening in its upper end and with weakened lines of severance extending outwardly from the side edges defining said central opening, into proximity to the outer edges of the envelope, and thence upwardly and inwardly toward the upper end of the wall, said lines of severance defining readily removable inner corner portions, said flap being adhesively secured to said removable corner portions, and also to the wall of the envelope below said corner portions and between the latter and the side edges of the envelope, said envelope being adapted to be opened by pulling said flap so as to break said last-mentioned adhesive bond, the adhesive bond between said flap and said removable portions being of such strength that said removable portions will remain united to the flap and be removed from the envelope wall, the upper portion of the wall from which said flap extends being outwardly 75 foldable upon itself along a line approximately

registering with the lower edge of said central opening in said other wall, thereby to expose an end portion of said inner container.

3. A package of the class described comprising an inner, material-containing envelope, an outer envelope having closed ends and an internal length only slightly greater than the external length of said inner envelope, whereby the closed ends of said outer envelope are effective to hold the walls thereof in tight frictional engagement with the walls of the inner envelope adjacent the ends of the package, thereby to resist shifting of the inner envelope in the outer envelope, one of said closed ends of the outer envelope comprising a flap extending from the upper end of one of the walls of the envelope, said flap being folded over the outside of the other wall to close the envelope, said other wall being provided with a centrally disposed opening in its upper end and with weakened lines of severance extending outwardly from the side edges defining said central opening, into proximity to the outer edges of the envelope, and thence upwardly toward the upper end of the wall, said lines of severance defining readily removable inner corner portions, said flap being adhesively secured to said removable corner portions and also to the wall of the envelope below said corner portions and between the latter and the side edges of the envelope, said outer envelope being adapted to be opened by pulling said flap from said other wall so as to break said last mentioned adhesive bond, the adhesive bond between said flap and said removable portions being of such strength that said removable portions will remain united to the flap and be removed from the outer envelope wall to thereby enlarge said centrally disposed opening so as to expose substantially the entire width of the upper end portion of said inner envelope, said inner envelope being so disposed in the outer envelope as to be substantially centrally located relative to said enlarged opening, thereby facilitating folding of the upper portion of the flap-carrying wall away from the exposed portion of the inner envelope, to thereby afford free access to the latter.

4. An envelope having a pair of walls and a closure flap extending from the upper end of one of said walls, said flap being folded over the outside of the other wall to close the envelope, said other wall being provided with a centrally disposed opening in its upper end, and with weakened lines of severance extending outwardly from the side edges defining said central opening, and into proximity to the outer edges of said envelope, there being additional lines of severance extending upwardly from the outer ends of said first mentioned lines of severance co-operating with the latter to define readily removable inner corner portions of said other wall, said flap being adhesively secured to said removable corner portions and also to said other wall of the envelope adjacent but outwardly of said lines of severance, said envelope being openable by pulling said flap so as to break said last-mentioned adhesive bond, the adhesive bond between said flap and said corner portions being of such strength that said corner portions will remain united to the flap, and be removed from the envelope wall, the upper portion of the wall from which said flap extends being outwardly foldable upon itself along a line approximately registering with the lower edge of said central opening when the envelope is opened, thereby to permit an element

contained in the envelope to project therefrom in readily accessible position.

5. A package of the class described comprising an inner container and an outer envelope enclosing said inner container, said envelope having a pair of walls and a closure flap extending from the end of one of said walls and folded over the adjacent end portion of the other wall to close the envelope, said other wall being provided with weakened lines of severance cooperating with the adjacent end edge of the wall to define removable wall material, said lines of severance embodying side portions adjacent but spaced inwardly from the side edges of the wall and extending downwardly from said end edge and lower portions of said lines of severance extending inwardly from said marginal side portions, said flap being adhesively secured in closed position to said removable wall material and also to said marginal side portions, the adhesive bond for said marginal side portions being weak enough to be breakable by pulling said flap away from said other wall, and the adhesive bond between said flap and said removable material being strong enough to cause said material to follow the flap and be separated from the wall when said flap is pulled therefrom, the upper end portion of the flap-bearing wall being bendable away from said inner container after separation of said removable material from said other wall, whereby a portion of said inner container may be caused to project from said outer envelope and thereby made readily accessible for withdrawal from said outer envelope.

6. A package of the class described comprising an inner container and an outer envelope enclosing said inner container, said envelope having a pair of walls and a closure flap extending from the end of one of said walls and folded over the adjacent end portion of the other wall to close the envelope, said other wall being provided with weakened lines of severance cooperating with the adjacent end edge of the wall to define removable wall material, said lines of severance embodying side portions adjacent but spaced inwardly from the side edges of the wall and extending downwardly from said end edge so as to provide narrow marginal side portions of the wall outwardly of said side portions of said lines of severance, there being also lower portions of said lines of severance extending inwardly from said marginal side portions, said flap being adhesively secured in closed position to said removable wall material and also to said marginal side portions and to said other wall below said removable material, the adhesive bond to said side portions and below said removable material being weak enough to be breakable by pulling said flap away from said other wall, and the adhesive bond between said flap and said removable material being strong enough to cause said material to follow the flap and be separated from the wall when said flap is pulled therefrom, the upper end portion of the flap-bearing wall being bendable away from said inner container after separation of said removable material from said other wall, and said narrow marginal side portions of the wall being readily displaceable by said inner container as an incident to such bending of said flap-bearing wall, whereby a portion of said inner container may be caused to project from said outer envelope and thereby made readily accessible for withdrawal from said outer envelope.
